DIE CUSHION

Howard D. Aldredge, Dayton, Ohio

Application June 3, 1944, Serial No. 538,567

9 Claims. (Cl. 267—1)

1

This invention relates to a hydraulically operated die-cushion that is adapted to be used on forming presses or punch presses of various types.

An object of the invention is to provide a die-cushion that is constructed and arranged as a unit structure that can be placed upon any forming press to provide a cushion for any part of a die that is supported upon the die cushion.

Another object of the invention is to provide a hydraulically operable die-cushion that is constructed and arranged in the manner of a bolster-plate that can be placed upon any forming press beneath a die member so that any part of the die requiring a cushioning action can be operably connected to the die-cushion to obtain the desired cushioning action of the die parts.

Still another object of the invention is to provide a unitary structure of a bolster-plate having a hydraulically operated die-cushion associated therewith as a part of the unit structure so that the bolster-plate can be placed upon any forming press and thereby provide a die-cushion on substantially any conventional forming press, even though the forming press was not constructed and designed for a die-cushion.

Another object of the invention is to provide a bolster-plate having a die-cushion therein in accordance with any of the foregoing objects wherein the die-cushion is hydraulically operated, and the fluid system for the die-cushion is wholly contained as a part of the unit structure, whereby the die-cushion can be used on any forming press without requiring external connections to the die-cushion.

Further objects and advantages will become apparent from the drawings and the following description:

In the drawings:

Figure 1 is a perspective elevational view of a mechanical press upon which the combination bolster-plate and die-cushion of this invention has been placed.

Figure 2 is a side elevational view, particularly in cross-section, illustrating the bolster-plate and die-cushion of this invention.

Figure 3 is an exploded perspective view of the bolster-plate and die-cushion of this invention with parts thereof broken away to illustrate the construction thereof.

Figure 4 is a vertical cross-sectional view taken substantially along line 4—4 of Figure 3.

Figure 5 is a cross-sectional view through the bolster-plate and die-cushion of this invention.

2

Figure 6 is a cross-sectional view similar to Figure 5 illustrating the mechanism in action.

Figure 7 is an enlarged cross-sectional view taken along line 7—7 of Figure 3.

Figure 8 is an elevational view of the die-cushion, partially in cross-section, illustrating a modified arrangement of a fluid control valve for the operating system of the die-cushion.

The combination bolster-plate and die-cushion 10 of this invention is adapted to be applied to any conventional forming press wherever and whenever a die-cushion is desired to be provided upon the forming press. Many of the standard line forming presses manufactured today do not have 15 die-cushions provided on them. However, in many instances it is desired to produce a piece upon a forming press of a type that requires a cushioning action to at least one part of the die to prevent the metal being formed from tearing 20 or being pierced during the forming operation. However, in the standard line of forming presses that are not provided with die-cushions, such a piece could not readily be formed on them, hence requiring the necessity of purchasing a special 25 forming press, or requiring the necessity of constructing a special die that may have a cushion incorporated therein for the purpose of cushioning the particular element desired. In the latter instance it is necessary to connect the cushioning member with a suitable fluid source for supplying the required fluid during operation of the cushioning member.

In this invention a special combination bolster-plate and die-cushion is constructed as a unitary structure with the fluid actuating system for the die-cushion being an integral part of the combination structure. The arrangement therefore permits placement of the bolster-plate and die-cushion upon any conventional press that is not 35 so provided with a die-cushion and thereby adapt the standard press for cushioning action of various elements of a die. The die can be constructed in conventional manner with the usual pins extending through the die from the elements to be 40 cushioned, these pins engaging the die-cushion in the bolster-plate of this invention for the purpose of cushioning the elements in the die during the forming operation.

The combination bolster-plate and die-cushion 50 of this invention, generally indicated by the numeral 10, is adapted to be used upon a forming press of any conventional type, one of which is illustrated in Figure 1.

The forming press consists of a frame 11 having a bed 12 that is adapted to support a die mem-

ber upon the same. The frame 11 carries the up-rights 13 that support a reciprocating ram 14 that is adapted to carry a punch or die member that cooperates with the die member carried upon the bed 12. The ram 14 is carried upon a crank 15 suitably driven through the pulley flywheel 57 for reciprocating the ram 14.

Under normal conditions the female die member will be supported upon the bed 12, and the male die member carried by the ram 14 so that the metal pieces placed upon the female die member can be formed upon reciprocation of the ram 14. When using the combination bolster-plate and die-cushion of this invention, the bolster-plate is supported upon the bed 12, and then the female die member is placed upon the bolster-plate 10, and the press can be operated in conventional manner and the elements of the die member can be cushioned by the die-cushion in a manner which will be hereinafter described.

The die-cushion of this invention consists of a bolster-plate 16 that is adapted to be placed upon the bed of any conventional forming press. The bolster-plate 16 has an opening 17 therein that receives the cushion plate 18 of the hydraulically operated die-cushion. The cushion plate 18 is connected to a piston 19 that operates in a cushioning cylinder 20 that has the cylinder bore 21 which receives the piston 19. A rod 22 extends between the piston 19 and the cushion plate 18 through an end closure wall 23 secured to the cylinder bore 21 to thereby form a closed cylinder chamber.

The cylinder 20 is provided with a flange 24 that receives the bolts 25 for securing the cylinder 20 to the lower side of the bolster plate 16. A spring 26 positioned between the piston 19 and the bottom wall of the cylinder 20 normally holds the piston 19 and the cushion plate 18 in an upward position as illustrated in Figure 5. The spring 26 is of sufficient strength to support the parts previously mentioned together with the parts of the die that are to be cushioned so that they will always be returned to the initial starting position, such as that illustrated in Figure 5.

The bolster plate 16 is adapted to support a die 30, which is secured thereto in any suitable and conventional manner. The die 30 is provided with the die opening 31 which receives the cushioning member 32 that has pins 33 extending therefrom into engagement with the cushion plate 18 of the die cushion. A male forming member 34 carried by the ram 14 is adapted to enter the die opening 31 for forming the work piece 35, the member 32 cushioning the work piece 35 by operation of the die-cushion in a manner hereinafter described.

The bolster plate 16 is provided with a pair of bores 36 and 36a extending through the same. The bore 36 receives the pistons 37 and 37a for reciprocation therein while the bore 36a receives the pistons 38 and 38a for reciprocation therein. The arrangement of each of the pistons 37, 37a, 38 and 38a is the same for each, hence a cross-sectional view of only one of the pistons has been illustrated, and is more clearly shown in Figure 7.

The piston 37a that operates within the bore 36 is retained against a stop-shoulder 39 provided by a smaller-diameter portion 40 of the bore 36 by means of a spring 41 that is retained in the bore 36 by means of the removable plug 42. The pistons 37, 37a, 38 and 38a are thus retained in a normal predetermined position. The spring 41 may be provided with suitable mechanism for

adjusting the degree of compression thereof to change the pressure at which the cushion plate 18 will operate, or the springs can be changed in their respective bores when a pressure change is required for operating the cushion plate 18.

The bore 40 provided between the pistons 37 and 37a, and the bore 40a provided between the pistons 38 and 38a are inter-connected by means of the passage 43 provided therebetween. The passage 43 is connected to the cylinder bore 21 by means of the passage 44 so that liquid in the cylinder bore 21 can be transferred through the passages 44 and 43 into the bores 40 and 40a to apply pressure against the pistons 37, 37a, 38 and 38a and cause them to move against the springs retaining them in position and thereby cause pressure to be developed in the cylinder chamber 21 that resists downward movement of the piston 19 as illustrated by the resistance of the springs 41, and thus resisting downward movement of the cushion plate 18 which causes the member 32 to cushion the work-piece 35 during the forming operation.

By controlling the force of the springs 41, the pressure developed in the chamber 21 can be controlled, or the pressure developed in the chamber 21 can be controlled by means of a restriction valve 50 that has the end thereof protruding into the passage 43 whereby to restrict the flow of liquid from the chamber 21 through the passage 44 into the passage 43. The resistance valve 50 therefore controls the pressure developed in the chamber 21 by regulating the pressure drop between the passage 44 and the passage 43 across the restriction valve 50.

The resistance valve 50 consists of a stem 45 that has the threaded portion 46 thereon that is received in the threaded recess 47 in the bolster plate 16, the resistance valve 50 extending from the threaded portion 46 of the stem 45. A packing member 48 is provided around the stem 45 to prevent loss of fluid around the resistance valve 50, and the valve 50 is moved inwardly or outwardly upon rotating the same by means of the knurled knob 49.

The operation of the device, thus far described, is such that when the ram 14 moves downwardly to cause the punch 34 to engage the work-piece 35, it will be forced downwardly against the member 32, which in turn forces the cushion-plate 18 downwardly. Downward movement of the piston 19 causes liquid in the chamber 21 to be delivered into the bores 40 and 40a in the bolster-plate 16 through the passages 44 and 43. Pressure will build up in the cylinder chamber 21 as determined by the springs 41 or by the pressure drop across the restriction valve 50 to thereby cushion the downward movement of the member 32 and thus support the work-piece 35 during the forming operation.

After the work-piece 35 is formed, as illustrated in Fig. 6, the ram 14 will move upwardly and thereby permit the spring 26 to lift the piston 19. The springs 41 in the bores in the bolster plate 16 will also cause inward movement of the pistons 37, 37a, 38 and 38a to return the fluid from the bores 40 and 40a through the passages 43 and 44 into the cylinder chamber 21, thus causing the piston 19 to rise and refill the cylinder chamber 21 in preparation for the next cycle of operation.

During operation of the cushioning device, there may be a certain amount of leakage past the piston 19 to the upper side thereof, and past the pistons 37, 37a, 38 and 38a into the respective

spring chambers associated therewith. Since the hydraulic system of the die-cushion is a self-contained system, it will be necessary to return this leakage fluid into the operating system to insure that the cylinder chamber 21 is always completely full of liquid at the end of its up-stroke so that the cushion-plate 18 can act immediately to support the member 32 when the punch 34 strikes the work-piece 35.

To provide for return of the leakage fluid, heretofore mentioned, into the operating system, the spring chambers behind the pistons 37 and 37a are interconnected by means of a passage 51 provided in the bolster-plate 16, and the spring chambers behind the pistons 38 and 38a are interconnected by means of a similar passage 51a. A passage 52 interconnects the spring chambers behind the pistons 37a and 38a, which in turn connects with a passage 53 that connects to a reservoir chamber 54 contained in the boss 55 carried along the side of the cylinder 21. A passage 56 connects between the reservoir chamber 54 and the upper side of the piston 19 to permit fluid to pass from above the piston 19 into the reservoir chamber 54. The reservoir chamber 54 is provided with a vent opening 70 so that the liquid can drain into the reservoir chamber by gravity.

To provide for return of liquid from the reservoir chamber 54 to the cylinder chamber 21, a check-valve 58 is provided between the outlet passage 59 from the reservoir chamber and the inlet passage 60 into the cylinder chamber 21.

The check-valve 58 is normally retained in a closed position by means of the spring 61 so that during the down-stroke of the piston 19 there will be no loss of fluid from the operating hydraulic system of the die cushion. However, during the upstroke of the piston 19, if there is insufficient fluid to completely fill the chamber 21 at the end of the upstroke of the piston 19, liquid can be drawn from the reservoir chamber 54 through the check-valve 58 into the cylinder chamber 21 to thereby completely fill the same and condition the chamber for the next cycle of operation.

The resistance valve 50, illustrated in Figure 4, will provide a resistance to flow of liquid between the passages 43 and 44 in either direction of flow. However, if it is desired to obtain an unimpeded flow of liquid into the cylinder chamber 21 during the upstroke of the piston 19, a resistance valve of the type illustrated in Figure 8 can be used. In this arrangement a valve member 65 is spring-pressed to closed position against the valve opening 66 by means of a spring 67, a cage 68 retaining the same in position adjacent the valve opening 66. The valve member 65 is regulated as to its open position by means of a rod 69 that is operated by suitable means extending exteriorly of the bolster plate 16, such as the knurled knob 49. In this latter instance, however, the stem 45 would carry an eccentric to engage the rod 69 and thus control the opening of the valve member 65 to regulate the resistance between the valve member 65 and the opening 66 when fluid is flowing in an upward direction through the passage 44. However, when fluid is flowing downwardly through the passage 44, and thus downwardly through the opening 66, the valve member 65 can leave the end of the rod 69 and compress the spring 67 to provide a full and free opening for passage of fluid through the valve opening 66.

While the apparatus disclosed and described herein constitutes a preferred form of the invention, yet it will be understood that it is capable

of mechanical illustration without departing from the spirit of the invention, and that all modifications that fall within the scope of the appended claims are intended to be included herein.

5 Having thus fully described my invention, what I claim as new and desire to secure by Letters Patent is:

1. In combination, a bolster plate member adapted to rest upon the bed of a forming press and support a forming die, said plate having an opening through the same, a cylinder chamber secured to the underside of said plate and beneath said opening and having a piston reciprocable therein, means carried by said piston and extending therefrom supporting a plate on the end thereof positioned within said opening that is reciprocable therein, a chamber in said bolster plate, means in said bolster plate chamber for effecting a change in the effective volume thereof for securing fluid therein, and a passage connecting said cylinder chamber with said bolster plate chamber to permit displacement of fluid therebetween upon reciprocation of said piston.
2. In combination, a bolster plate member adapted to rest upon the bed of a forming press and support a forming die, said plate having an opening through the same, a cylinder chamber secured to the underside of said plate and beneath said opening and having a piston reciprocable therein, means carried by said piston and extending therefrom supporting a plate on the end thereof positioned within said opening that is reciprocable therein, a chamber in said bolster plate, movable means in said bolster plate chamber for effecting a change in the effective volume of said chamber means for receiving fluid therein, means in said bolster plate chamber to resist the movement of said movable means until a determined pressure is built up in said chamber, and a passage connecting said bolster plate chamber with said cylinder chamber through which fluid is transferred from said cylinder chamber to said bolster plate chamber under pressure as caused by said resistance means during movement of said piston in one direction thereof.
3. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate in said opening, a chamber in said bolster plate having pressure resistance means therein for effecting a change in the effective volume of the chamber means when pressure is built up in the chamber means by liquid being transferred thereto, and passage means in said bolster plate and said cushioning cylinder hydraulically interconnecting said cushioning cylinder with said bolster plate chamber to permit an interchange of liquid under pressure therebetween upon a change in volume in the cushioning cylinder caused by reciprocable movement of the piston therein.
4. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate in said opening, a chamber in said bolster plate having pressure resistance means therein for

effecting a change in the effective volume of the chamber means when pressure is built up in the chamber means by liquid being transferred thereto, passage means in said bolster plate and said cushioning cylinder hydraulically interconnecting said cushioning cylinder with said bolster plate chamber to permit an interchange of liquid under pressure therebetween upon a change in volume in the cushioning cylinder caused by reciprocable movement of the piston therein, and resistance valve means in said passage means for resisting the movement of liquid from said cushioning cylinder to said bolster plate chamber means.

5. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate in said opening, a chamber in said bolster plate, piston means reciprocable in said bolster plate chamber and opposed in movement thereof in one direction by spring means contained in the said chamber, a passage in said bolster plate and said cushioning cylinder hydraulically connecting said cushioning cylinder with said bolster plate chamber whereby liquid can be transmitted from said cushioning cylinder into said bolster plate chamber to move said second piston means against said spring means and thereby develop hydraulic pressure in said cushioning cylinder to resist movement of the piston therein, and resistance valve means in said passage for resisting the flow of liquid from the cushioning cylinder to the chamber means to increase the pressure in the cushioning cylinder as determined by the pressure drop across the resistance valve means.

6. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate in said opening, a chamber in said bolster plate, piston means reciprocable in said bolster plate chamber and opposed in movement thereof in one direction by spring means, a passage in said bolster plate and said cushioning cylinder hydraulically connecting said cushioning cylinder with said bolster plate chamber whereby liquid can be transmitted from said cushioning cylinder into the said chamber to move said piston means against said spring means and thereby develop hydraulic pressure in said cushioning cylinder to resist movement of the piston therein, a passage for conducting hydraulic liquid that leaks past either of said piston means to a reservoir on said bolster plate, and a passage including a check valve therein connecting said reservoir with said cushioning cylinder to permit hydraulic liquid to flow from said reservoir to said cushioning cylinder periodically to refill the cushioning cylinder during reciprocation thereof of any liquid lost therefrom.

7. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate

in said opening for reciprocation therein, a chamber extending transversely through said bolster plate substantially paralleled with the upper surface thereof for receiving liquid from said hydraulic cushioning cylinder, piston means in said chamber, spring means in said chamber engaged by said piston means to oppose movement of said piston means in one direction, a passage in said bolster plate and said cushioning cylinder hydraulically connecting said cushioning cylinder with said bolster plate chamber whereby liquid can be transmitted from said cushioning cylinder into the said chamber to move said piston means against said spring and thereby develop hydraulic pressure against said cushioning cylinder to resist movement of the piston in the cushioning cylinder, a reservoir on said bolster plate for hydraulic liquid, and passage means connecting said reservoir with said cushioning cylinder whereby to supply said cylinder with liquid from said reservoir to refill the same during reciprocation of said piston in said cushioning cylinder.

8. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate in said opening for reciprocation therein, bores extending transversely through said bolster plate adjacent each side of the opening therein and substantially parallel to the upper surface of the bolster plate, a piston in each of said bores reciprocable therein for regulating the effective volume thereof to receive liquid from said hydraulic cushioning cylinder, spring means in each of said bores against which said pistons in the respective bores are urged, a passage hydraulically interconnecting said bores positioned in said bolster plate and said hydraulic cushioning cylinder whereby liquid can be transmitted from said hydraulic cushioning cylinder into said bores to move said pistons against the springs therein and thereby develop hydraulic pressure in said cushioning cylinder to resist movement of the piston in the cushioning cylinder, a liquid reservoir in said cushioning cylinder, and a passage including a check valve therein hydraulically connecting said reservoir with said cushioning cylinder to permit hydraulic liquid to flow from the reservoir to said cushioning cylinder to refill the same during the reciprocation thereof of any lost liquid.

55. 9. In combination, a bolster plate member adapted to be positioned upon the bed of a forming press and support a die and having an opening therethrough, a hydraulic cushioning cylinder positioned on one side of said plate in substantial alignment with said opening and having a piston therein supporting a cushioning plate in said opening for reciprocation therein, bores extending transversely through said bolster plate adjacent each side of the opening therein and substantially paralleled to the upper surface of the bolster plate, a piston in each of said bores reciprocable therein for regulating the effective volume thereof to receive liquid from said hydraulic cushioning cylinder, spring means in each of said bores against which said pistons in the respective bores are urged, a passage hydraulically interconnecting said bores positioned in said bolster plate and said hydraulic cushioning cylinder whereby liquid can be transmitted from said hydraulic cushioning cylinder into said bores to

move said pistons against the springs therein and thereby develop hydraulic pressure in said cushioning cylinder to resist movement of the piston in the cushioning cylinder, a liquid reservoir in said cushioning cylinder, and a passage hydraulically connecting said bores and said cushioning cylinder with said reservoir for conducting to said reservoir hydraulic liquid that leaks past either the pistons in said bores or the piston in said hydraulic cushioning cylinder.
